BATHING SUIT

Salvatore F. De Benedetto, Brooklyn, N. Y.

Application November 14, 1934, Serial No. 752,913

14 Claims. (Cl. 2—67)

The present invention relates to bathing suits, and has for a general object the provision of a "strapless" bathing suit which is free from supporting straps commonly positioned over the shoulders or about the neck of the wearer, is attractive, comfortable and efficiently self-supporting.

A more particular object of the present invention is the provision of such a bathing suit which is free from shoulder straps or similar supporting means positioned over the shoulders or about the neck of the wearer and efficiently self-supporting to cover the chest of the wearer; fits snugly and comfortably, tending to give the wearer more freedom than do the usual types of suits, presents a pleasing appearance, and allows the wearer to obtain an even sun-tan on the shoulders and neck and, if desired, on the back unmarred by pale stripes common to the use of strap-supported bathing suits.

A further object is the provision of such a bathing suit which is provided with supporting means at the waist of a wearer upon which is supported relatively stiff resilient members adapted to fit the body of the wearer and efficiently to support the upper portion of the suit adapted to cover the chest of the wearer.

Other objects of the invention will in part be obvious and will in part appear hereinafter.

The invention accordingly comprises an article of manufacture possessing the features, properties, and the relation of elements which will be exemplified in the article hereinafter described and the scope of the invention will be indicated in the claims.

For a fuller understanding of the nature and objects of the invention reference should be had to the following detailed description taken in connection with the accompanying drawings, in which:

Fig. 1 is a front view with parts broken away of one form of the bathing suit of the present invention;

Fig. 2 is a rear view thereof;

Fig. 3 is a perspective view of the rear side of the supporting member used therein;

Fig. 4 is a detailed sectional view with parts broken away taken on line 4—4 of Fig. 2;

Fig. 5 is a rear view of a modified form of the present invention;

Fig. 6 is a perspective view of the rear side of the supporting member used in the form shown in Fig. 5;

Fig. 7 is a rear view of a further modification;

55 and

Fig. 8 is a perspective view of the rear side of the supporting member used in the form shown in Fig. 7.

In accordance with the present invention a "strapless" bathing suit is provided which is self-supporting and free from the usual supporting means positioned over the shoulders or about the neck of a wearer. This is accomplished by means including a relatively stiff member, that is, an elongated semi-rigid member of resilient material such as a narrow strip of flat spring steel, metallic wire, bone, suitable composition and the like. This member is shaped to fit across the chest of the wearer, under the arms and to extend down to supporting means at the waist of the wearer. The supporting means at the waist is preferably a belt of relatively heavy stiff material such as leather or heavy woven material. The belt may be positioned either externally or internally of the bathing suit and is made suitably adjustable, as by means of adjustable fasteners, buckles, an elastic section, or by formation from a suitably heavy and stiff elastic material. The adjustable feature is necessary to allow the waist of the bathing suit to be pulled up over the hips of the wearer.

The supporting member has at least the front portion adapted to cross the chest of the wearer fastened to the bathing suit in any suitable manner, preferably by turning the edge of the suit thereover and stitching the turned over edge to the body of the suit. To make certain that the supporting member does not fall forward various means may be used. In a bathing suit having a portion covering the back of the wearer the back portion serves this purpose. By having the side portions of the supporting member fitted around the body of the wearer and converging down the back such tendency is avoided. This result may be augmented by the use of auxiliary ties or straps, preferably adjustable, extending between the side portions. A similar function is performed by the structure of the preferred form of supporting means wherein the ends of the supporting member are rigidly secured to the relatively stiff supporting belt.

Referring to the drawings, like numerals refer to like parts throughout. A bathing suit shown therein comprises a main body portion 10 of any suitable material such as knitted fabric having an upper part 11 adapted to cover the chest of a wearer. In the modification shown in Fig. 1, the upper part 11 is secured to a member 12 of relatively stiff material, that is, an elongated semi-rigid member of resilient material, for ex-

ample, spring steel. The member 12 comprises a portion 13 adapted to cross the chest of the wearer and side members 14, 14 adapted to fit under the arms and down the back of the wearer. 5 The side portions 14, 14 converge, as is shown in Fig. 2, have their ends 15, 15 supported upon a belt 16 at the waist of the body portion 10, and preferably are secured thereto by means such as rivets 17. The securing means, such as rivets 10 17, may also serve to secure the ends 15, 15 and the belt 16 to the body 10. The belt 16 is further secured to the body 10, when the ends 15, 15 are secured to the belt, by means of the marginal portion 18 of the upper part of the body which 15 is shown turned over and stitched to the body of the suit to cover the member 12. The belt 16 is made suitably adjustable as by means of a buckle 19.

When desired suitable means are provided for 20 securing side portions 14, 14 together to insure against the upper part of the body of the suit falling away from the body of the wearer. Such means may comprise ties or straps 20, 20 secured in any suitable manner to the side portions 25 14, 14, for example by rivets or eyelets 21, as shown in detail in Fig. 4. These straps are preferably provided with adjustable means such as buckles 22, 22 and a strap 23 is preferably provided with end loops 24 and 25 respectively to 30 receive the belt 16 and the ties or straps 20, 20.

In the modified form shown in Figs. 5 and 6, the side portions 14, 14 are crossed at the back and secured to the belt 16 in any suitable manner, either through the body 10 and on top of the 35 belt 16 or underneath the body 10 and belt 16, by suitable means such as rivets 17. Crossing of the side portions 14, 14 avoids any necessity of the use of ties or straps therebetween across the back although such auxiliary tying means 40 may be used if desired. The elimination of the tying straps across the back, however, will allow the wearer to obtain a sun-tanned back unmarred by pale stripes that may be caused by ties or straps.

45 In Figs. 7 and 8 another modified form is shown wherein the belt 16 is mounted internally of the body 10 of the bathing suit. In this form when the belt is made adjustable by the use of the buckle 19, such means for adjustment are preferably disposed at the back, as shown, to allow ready access thereto.

It is obvious that many modifications within 55 the scope of the invention are possible. Any desired openwork or openings may be provided in the body of the bathing suit. Auxiliary tying means of various shapes and combinations may be positioned across the back at various points from a short distance above the waist line to just below the neck line, which may be secured to side 60 portions of the upper supporting members or to the body of the bathing suit. In the modification shown in Figs. 5 and 6, the crossing side portions may be detachably secured together at the point of crossing after the suit has been put on. In 65 the modifications shown in Figs. 1 to 3 inclusive, and 7 and 8, the converging side portions may be spaced farther apart or closer together, even substantially meeting at the belt. In the latter case adjustment of the internally positioned belt may 70 be had by the use of an elastic section in the belt or by the use of elastic material in its formation.

Since certain changes may be made in the 75 above article and different embodiments of the invention could be made without departing from

the scope thereof, it is intended that all matter contained in the above description or shown in the accompanying drawings shall be interpreted as illustrative and not in a limiting sense.

It is also to be understood that the following 5 claims are intended to cover all of the generic and specific features of the invention herein described, and all statements of the scope of the invention which, as a matter of language, might be said to fall therebetween. 10

Having described my invention, what I claim as new and desire to secure by Letters Patent, is:

1. A strapless bathing suit comprising in combination an upper body part adapted to cover the chest of a wearer, a supporting belt adapted 15 to be disposed at the waist of the wearer, and an elongated semi-rigid member of resilient material shaped to fit across the chest, under the arms and down the back with the portions down the back converging and the ends thereof supported on said belt at the back, said body portion having the upper marginal edge thereof fastened to said resilient member. 20

2. A strapless bathing suit comprising in combination a body portion having an upper part 25 adapted to cover the chest of a wearer, an external belt at the waist of said body portion to be secured adjustably about the wearer, and an elongated semi-rigid member of resilient material comprising a portion fastened to the upper marginal portion of said upper part to extend across the chest of the wearer and side portions fastened to said body portion shaped to fit under the arms and converging down the back of the wearer with the ends thereof supported at the 30 back on said belt. 35

3. A strapless bathing suit comprising in combination a body portion having an upper part 40 adapted to cover the chest of a wearer, an external belt fastened at the waist of said body portion to be secured adjustably about the wearer, and an elongated semi-rigid member of resilient material secured to and covered by the upper edge 45 of said body portion comprising a portion to extend across the chest of the wearer and side portions shaped to fit under the arms and converging down the back of the wearer with the ends thereof rigidly secured to said belt. 50

4. A strapless bathing suit comprising in combination a body portion having an upper part 55 adapted to cover the chest of a wearer, a belt at the waist of said body portion to be secured adjustably about the wearer, and an elongated semi-rigid member of resilient material comprising a portion to extend across the chest of the wearer fastened to the marginal portion of said upper part and side portions shaped to fit under the arms and converging down the back of the wearer without crossing with the ends thereof supported on said belt. 60

5. A strapless bathing suit comprising in combination a body portion having an upper part 65 adapted to cover the chest of a wearer, an external belt fastened at the waist of said body portion to be secured adjustably about the wearer, and an elongated semi-rigid member of resilient material secured to and covered by the upper edge 70 of said body portion comprising a portion to extend across the chest of the wearer and side portions shaped to fit under the arms and converging down the back of the wearer without crossing with the ends thereof rigidly secured to said belt. 75

6. A strapless bathing suit comprising in combination a body portion having an upper part 75

- adapted to cover the chest of a wearer, an external belt fastened at the waist of said body portion to be secured adjustably about the wearer, an elongated semi-rigid member of resilient material secured to and covered by the upper edge of said body portion comprising a portion to extend across the chest of the wearer and side portions shaped to fit under the arms and converging down the back of the wearer without crossing with the ends thereof rigidly secured to said belt, and means in the back tying said side portions together. 5
7. A strapless bathing suit comprising in combination a body portion having an upper part adapted to cover the chest of a wearer, an internal belt at the waist of said body portion to be secured adjustably about the wearer, and an elongated semi-rigid member of resilient material secured to and covered by at least the front part of the marginal portion of said body portion comprising a portion to extend across the chest of the wearer and side portions shaped to fit under the arms and converging down the back of the wearer with the ends thereof supported on said belt. 10
8. A strapless bathing suit comprising in combination a body portion having an upper part adapted to cover the chest of a wearer, an internal belt fastened at the waist of said body portion to be secured adjustably about the wearer, and an elongated semi-rigid member of resilient material secured to and covered by the upper edge of said body portion comprising a portion to extend across the chest of the wearer and side portions shaped to fit under the arms and converging down the back of the wearer with the ends thereof rigidly secured to said belt. 15
9. A strapless bathing suit comprising in combination a body portion having an upper part adapted to cover the chest of a wearer, a belt at the waist of said body portion to be secured adjustably about the wearer, and an elongated semi-rigid member of resilient material comprising a portion to extend across the chest of the wearer fastened to the marginal portion of said upper part and side portions shaped to fit under the arms of the wearer and crossing in the back with the ends thereof supported on said belt. 20
10. A strapless bathing suit comprising in combination a body portion having an upper part adapted to cover the chest of a wearer, a belt fastened at the waist of said body portion to be secured adjustably about the wearer, and an elongated semi-rigid member of resilient material secured to and substantially covered by the upper edge of said body portion comprising a portion to extend across the chest of the wearer and side portions shaped to fit under the arms of the wearer and crossing in the back with the ends thereof rigidly secured to said belt. 25
11. A garment comprising in combination an upper body part adapted to cover the chest of a wearer, supporting means adapted to be dis-
- posed at the waist of the wearer, a member of stiff material fastened to the upper portion of said body part across the front, a pair of stiff supporting members mounted on said supporting means at the back shaped to pass upwardly under the arms of a wearer and supporting said member across the front, and means to secure said supporting members together positively to prevent them from falling forward. 30
12. A bathing suit comprising in combination an upper body part adapted to cover the chest of a wearer, supporting means adapted to be disposed at the waist of the wearer, a semi-rigid member of resilient material having a portion adapted to cross the chest fastened to the upper portion of said body part and side portions passing under the arms and down the back of the wearer with the ends thereof supported on said supporting means, and means tying said side portions together. 35
13. A garment comprising in combination an upper body part adapted to cover the chest of a wearer, supporting means adapted to be disposed adjacent the waist of the wearer, a pair of semi-rigid supporting members supported at the back on said supporting means and shaped to pass upwardly under the arms of a wearer, means securing said members to said upper body part whereby the latter is supported, a flexible tie having each of its ends secured to one of said semi-rigid members in the vicinity of the shoulder blade of the wearer when the garment is worn, said tie constituting two portions converging downwardly and meeting substantially medially, means to secure said tie to said supporting means, and adjustable means for cooperation with said tie and said last mentioned means to foreshorten the distance between said semi-rigid members at the points of securement of said tie thereto. 40
14. A garment comprising in combination an upper body part adapted to cover the chest of a wearer, stiffening means associated with the upper body part adapted to extend across the chest of the wearer toward the arm-pits, supporting means adapted to be disposed at the waist of the wearer, and a pair of relatively stiff supporting members located in the back, each having its lower end supported on said supporting means at the waist in the vicinity of the small of the back of the wearer and its upper portion extending upwardly toward the arm-pit of the wearer when the garment is worn with said upper portion of said supporting member secured to an adjacent portion of said upper body part and associated stiffening means, said relatively stiff supporting members having at least their upper portions laterally spaced apart in the vicinity of the shoulder blades of the wearer and cooperating with said stiffening means to support the portion of said garment covering the chest of the wearer. 45
